BACK CONSTRUCTION FOR MECHANICAL BINDERS

Clarence Damon Trussell, Pine Castle, Fla.

Application May 9, 1958, Serial No. 734,303

3 Claims. (Cl. 129—1)

The herein disclosed invention relates to bindings of the mechanical type illustrated in Trussell Patent No. 2,645,816 of July 21, 1953, in which the binder rings are carried by a spine or backbone of tubular formation.

Objects of the invention are to provide a suitable back for such bindings, for carrying lettering or other identification such as present on most books and for covering the mechanical features and giving the binding a finished book appearance.

It is an object of the invention to accomplish all of this in a simple, practical and inexpensive form of construction.

Further special objects of the invention are to provide a back construction for mechanical binders which may be readily applied to the binder and, if desired, be readily removed, thus to enable the use of the same or different backs on binders containing the same or different subject matter.

Other desirable objects and the novel features through which the purposes of the invention are attained are set forth and will appear in the course of the following specification.

The drawing accompanying and forming part of the specification is illustrative of several different embodiments of the invention but such structure may be further modified and changed as regards the immediate illustration, as will be apparent from the following description and claims wherein the invention is more fully defined.

In the drawings—

Fig. 1 is a perspective view of a mechanical binding having the invention incorporated therein.

Figs. 2 and 3 are broken cross sectional views on the line 3—3 of Fig. 1 showing the back in separated and in combined relation with the binder.

Fig. 4 is a broken part sectional side elevation showing the back in position about to be applied to the binder.

Fig. 5 is a similar view on a larger scale showing the back interlocked with the binder.

Figs. 6 and 7 are broken end elevations illustrating a modification in which the back is interlocked with the binder by a longitudinal sliding movement instead of being sprung into the tubular back element, as first illustrated.

Fig. 8 is an end elevation of another modification in which the back member, as in the last mentioned form, has companion jaw elements enabling it to be slid longitudinally into engagement with the back portion of the binder or possibly be snapped over the edges of the tubular or oval back element of the binder.

Fig. 9 is an end view of another modification.

In the first illustrated embodiment of the invention the binder is made up of a tubular rib or spine 10 having ring forming fingers 11 integrally attached thereto at 12 and having their free ends caught in the opposite side of the tubular formation at 13.

This backbone structure is modified from the construction illustrated in the patent to the extent that the

2

tubular rib is cut open at the bottom, as indicated at 14, to permit the entry of interlocking projections on a back plate which is to be combined therewith.

This plate which is to form the back of the binding 5 is designated 15 and is shown as a generally flat plate of approximately the length and width of the binder, so as to provide a more or less complete cover for the binding and it is shown particularly in Figs. 2 and 4 as carrying circular lugs or projections 16, along the center, of a size and spaced to closely fit in the tubular backbone between the rings, as in Figs. 3 and 5.

The back plate 15 and attaching lugs 16 may be of metal, plastic or other suitable materials and this plate may be flat with curved edges, as in Figs. 1 and 2, or be rounded as a book back or be otherwise shaped as desired.

Also it may have lettering or indicating data directly applied thereto or possibly applied by cards attached by adhesive or inserted in card holders formed on or carried 20 by the back plate.

The attaching lugs 16 and the receiving opening 14 provided therefor in the tubular rib are preferably such as to require the forceful springing of the back plate into interlocked engagement on the backbone structure, thus to eliminate the need for tools or other accessories and insuring that the back plate will remain in place with all ordinary handling of the binding.

Also it is to be noted that so engaged with the binder the back plate does not interfere in any way with the 30 opening of the bound pages and other full use of the binding.

While the interlock may be permanent for all general purposes or uses of the binder, preferably the yielding frictional engagement of the parts is such that the back 35 may be removed, if desired, by prying it loose from the binder.

The opening 14 for receiving the lugs on the back plate may be made by slotting the back of the rib the full length of the same or this slot may be terminated short 40 of one or both ends of the rib to reinforce the same and so as to leave a stop or stops at one or both ends to hold the back plate against longitudinal shifting movement on the binder. The slotting of the backbone has the effect of creating opposing spring fingers which will 45 yield to admit the lugs on the back plate into securely held engagement within the tubular rib. Thus secured the back plate provides a reinforcement for the binder and a convenient grip for handling the binder as a book.

In the form of the invention shown in Figs. 6 and 7 the attachment of the back plate 19 is effected by providing it with opposed longitudinally extending jaws 20 to engage over the longitudinally extending flanges 21 on the back of the tubular rib. These flanges may be 55 provided by attaching a strip having these edges, as indicated at 22, Fig. 6, or such flanges may be provided by striking lugs out of the sides of the tubular rib, proportioned to fit in the under cut channel provided by the opposed jaws 20 on the back plate.

Attachment of the back plate may be effected in this second form of the invention by sliding it longitudinally or springing it over the projecting edges on the back of the tubular rib.

Fig. 8 illustrates a modification in which the back member of the binder is of part oval rather than of completely tubular form, as shown at 23, the ring forming fingers 24 being integrally attached at one end at 25 and inserted through openings in the hollow backbone member at the opposite end 26.

This construction provides two longitudinally extending projecting edge flanges 27 enabling the use of a back

plate 28 having inturned edges 29 providing opposed longitudinally extending jaw elements engageable over the flanges by a longitudinal sliding or springing action.

Fig. 9 illustrates a modification similar to that shown in Figs. 6 and 7, but in which the edge flanges 21a of the binder are integral outturned edges of the tubular rib, instead of being provided by an added attached strip.

This is a more compact construction, using less material and possibly less expensive. The back in this case reinforces the tubular rib of the binding, preventing it from spreading.

It will be noted in the first illustrated form, Figs. 2, 3, 4 and 5, that the back will be held against longitudinal shifting movement by engagement of the projectors 16, between the ends of the ring forming fingers which project into the rib at 13.

In all forms illustrated, the back plate forms an outside finished cover for the back of the binder adapted to carry identifying data, such as a book title or the like, providing a finished book-like appearance, enabling handling and treatment as a book and all this without restricting the free opening character of the binder.

I claim:

1. Back construction for mechanical binders having binder rings connected by a tubular rib, comprising 25 a back plate, lugs on said back plate spaced to enter between said rings, said tubular rib having an opening in the back of the same to admit said lugs and the lugs

being of a size to closely fit within said tubular rib whereby to closely confine the back plate thereto.

2. Back construction for mechanical binders having binder rings connected by a tubular rib, comprising a back plate, said tubular rib being cut in the back of the same between the rings into opposed spring fingers and said back plate having lugs spaced apart and of a size to enter and be gripped between said spring fingers.

3. An outside back for a mechanical binder consisting of a tubular rib and spaced fingers carried by said rib and having free ends projecting within the rib, said tubular rib having openings in the back of the same between said fingers, said back plate carrying readable matter relating to contents of the binder and having projections on the inner face of the same of a size to enter through said openings and fit within said tubular rib and spaced to enter between the projecting ends of the fingers within the rib.
